UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

RUFFLING MECHANISM FOR SEWING-MACHINES.

1,273,156.

Specification of Letters Patent. Patented July 23, 1918.

Application filed September 2, 1915. Serial No. 48,595.

To all whom it may concern:

Be it known that I, ALBERT H. DE VOE, a citizen of the United States, residing at Westfield, in the county of Union and State 5 of New Jersey, have invented certain new and useful Improvements in Ruffling Mechanisms for Sewing-Machines, of which the following is a specification, reference being had therein to the accompanying drawings.

10 This invention relates to improvements in sewing machine rufflers, and has for its object to provide a machine adapted to gather a ribbon or the like into scallop-shaped series of ruffles and to secure the said ruffles 15 by stitching.

In the present embodiment of the improvements, the sewing mechanism comprises a reciprocatory needle and a rotary looper coöperating to form a single thread 20 chain-stitch, the feeding and presser-members being of usual form. The main-shaft of the sewing machine is disposed in bearings below the work-plate, and is provided with an eccentric for operating, through 25 suitable connections, the ruffler actuating rock-shaft fitted loosely within bearings above the work-supporting plate and having thereon a depending arm provided with a laterally projecting stud embraced by the 30 sleeve of a bracket formed with horizontally disposed channels to receive horizontally projecting members of two relatively-adjustable ruffler-blade carriers, a spring tending to tilt the bracket toward the work- 35 plate. The ruffler-blade carriers are movable toward and from each other by means of a lever fulcrumed upon the bracket and formed with apertures to receive pins projecting from the carrier-projections. Each 40 carrier *per se* is a flat horizontal plate having secured thereon at its forward end the shank of a pronged ruffler-blade, one plate being confined between the lower face of the second plate and a base-plate secured to 45 a depending flange on the said second plate, the edge of the first plate and the inner face of the flange on the second plate being parallel with the line of feed to serve as edge-guiding stops for the ribbon, the said members thus forming a ruffling guide. The 50 ruffler-actuating rock-shaft with the ruffling guide supported thereby is bodily moved endwise during the ruffling operation

through adjustable connections with a rotary cam given step-by-step movements 55 through mechanism similar to that described in United States patent to Diehl No. 541,840, dated July 2, 1895.

The operation of the ruffling device is such that after a ruffling stroke and the 60 penetration of the gathered ribbon by the needle, the ruffling guide is retracted and by its movement away from the point at which the ribbon is firmly held by the needle and presser-foot causes the pronged 65 blades to slide over the ribbon for a distance equal to the amount thereof thrust forward at the preceding ruffling stroke. The lateral movement of the ruffling guide during each 70 ruffling stroke results in the production of 70 series of ruffles in scallop formation, the blades being laterally moved in one direction during the production of a plurality of ruffles, in this case four, forming one half 75 of the scallop, a reverse movement of the blades being effected in the production of a like number of ruffles to complete the scallop.

In the drawings, Figure 1 is a front elevation of a machine embodying the improvements, and Fig. 2 is a plan view of the same, partly in section. Fig. 3 is a front elevation of the machine, and Fig. 4 is a detail perspective view of certain elements of the mechanism for imparting lateral movements 80 to the ruffling guide. Figs. 5, 6, 7, 8 and 9 are detail views of certain parts of the ruffling guide, and Fig. 10 is a view of the product. Fig. 11 is a cross section on line 85 11—11, Fig. 6.

The improvements are shown in connection with a machine comprising the bed A, standard B and overhanging arm C terminating in the hollow-head D overlying the work-supporting plate E. Journaled in 95 bearings formed within the standard B and bearing support A* is the main-shaft 1 provided at one end with the connected driving pulley 2 and balance-wheel 3, and carrying at its opposite end the rotary looper 4. 100 Journaled in the overhanging arm C is the needle-actuating rock-shaft 5 operatively connected by means of crank-arm 6 and link 7 with the needle-bar 8 supporting the needle 9, the shaft being actuated through 105 crank-arm 6* and pitman 3* driven by the

balance-wheel 3. The feeding device is of usual form and comprises the feed-bar 10 operatively connected at one end with the feed-actuating rocker 11 operated through 5 pitman 11^x having a strap embracing eccentric *e* and provided at its opposite end with a yoke 12 embracing the feed-lift eccentric 13 on the main-shaft 1, the feed-dog 14 being adjustably connected to an arm 10^x projecting laterally from the feed-bar 10.

The ruffler-actuating rock-shaft 16 is loosely mounted within the bearing bosses 15 projecting laterally from the standard B and head D, and has fixed thereon at one 15 end the slotted crank-arm 17, connected by means of the adjustable sliding connection 18 with a rock-lever 19 having its fulcrum-stud 20 fitted within an aperture formed in boss 21 projecting from the standard B. 20 The rock-lever 19 is formed with the laterally extending flanges 19^x to provide a channel-way to receive the slide-block 18^x forming a part of the adjustable connection 18. The lower end of rock-lever 19 is connected 25 by means of stud-screw 22 with the upper end of eccentric rod 23 provided at its lower end with a strap 23^x embracing the ruffler-actuating eccentric 24 on main-shaft 1.

Clamped upon the ruffler-actuating rock-shaft 16 near its forward end by means of the screws 25 is the split-sleeve 26^x of a rocker-arm comprising an upper section 26 formed with a channel 28 to receive the lower section 27 secured therein by means 35 of the clamping screws 29. The screws 29 enter a longitudinal slot in the upper section to permit vertical adjustment of the lower section and the members carried thereby. The lower rocker-arm section 27 is 40 formed with a threaded aperture to receive the reduced threaded end of a horizontally disposed stud 30 formed with a collar 30^x to abut the arm, a nut 31 serving to secure the stud in position. Loosely mounted upon 45 the stud 30 is the sleeve 32 of a bracket 33 formed with the seats or channels *c* and *c*^x to receive horizontally projecting members of the ruffler-blade carriers 34 and 35.

The ruffler-blade carrier 34 is a flat plate 50 having at its forward end a horizontally disposed slot to receive the shank of a ruffler-blade 36 formed with projecting fabric engaging prongs, the blade being secured in position by means of the set-screws 37. Integral with the carrier-plate 34 is an arm 38 formed with a projecting horizontally disposed lug 38^x fitted to slide within the channel *c*^x formed in the bracket 33. Depending from the carrier-plate 34 is a flange 55 55 to which is secured the upper face of a base-plate 40 between which and the carrier-plate 34 is slidably fitted the carrier-plate 35 to which is secured by means of the screws 41 the pronged ruffling blade 42, a

clearance space 34^x for the heads of said 65 screws being formed in the carrier-plate 34. The carrier-plate 35 is provided with an arm 43 its upper portion being bent horizontally to slidably fit within the channel *c* formed in the bracket 33. When the carrier-plates are in assembled position, as 70 shown in Fig. 1 a ribbon-guiding channel is provided between the plates 34 and 40, edge-guiding walls for the ribbon being provided by the inner wall of flange 39 and the edge 75 35^x of carrier 35.

The carrier-plates 34 and 35 are relatively adjustable to vary the width of the ribbon-guiding channel, and to this end the carrier-arms 38 and 43 are provided with pins *p* 80 which fit within the slots 44 of a shifting lever 45 pivotally connected at 47 to the bracket 33. The shifting lever is formed with a short handle 45^x and with a segmental slot *s*^x to receive a guide-pin 46 85 carried by the bracket 33. It will be understood that by moving the lever 45 to the left or right an adjustment may be made in the distance between the inner wall of the flange 39 of plate 34 and the edge 35^x of the plate 35 to accommodate various widths of ribbon. It will also be seen from Figs. 5 and 6 that the ruffling blades will engage the marginal portions of the ribbon, whatever the adjustment may be. The ruffling 95 guide is tilted forward under pressure toward the work by means of a coiled spring 48 surrounding the reduced portion 32^x of the bracket-sleeve 32, one end thereof engaging the upper face of carrier 34 and 100 its opposite end resting upon the projecting arm of a stop member 49 secured upon the depending rocker-arm 27.

To lay the ruffles in scallop formation, the ruffler-actuating rock-shaft with the ruffling guide supported thereby is intermittently and bodily moved during the ruffling operations. To this end, the rock-shaft 16 is embraced, between the collars 50^x clamped thereon, by the sleeve 50 of a depending arm 51 formed with a longitudinal slot to receive a slide-block 52 carried by a stud 53 formed at its inner end with a rectangular head 53^x adapted for sliding adjustment within an undercut channel formed in a rock-lever 54. The rock-lever 54 is provided at its upper end with a fulcrum-pin 55 loosely mounted within the horizontal sleeve 56 of a bracket-arm 57 secured upon the overhanging arm *c* by the screws 58. The stud 53 carrying slide-block 52 is threaded at its outer end to receive a washer 59 having clamped thereon the split hub 60^x of a short lever 60 by means of which the slide-block may be adjusted toward and from the fulcrum point of the rock-lever 54 and may be secured in its adjusted position.

To enable the operator to exactly adjust the point of connection between the rock-lever 54 and arm 51 to obtain a desired lateral throw of the ruffling guide, the stud 53 is embraced by the shank of, and carries with it, a pointer 61 bent into parallel relationship with the face of arm 51 and adjacent index lines formed on the outer face of the said arm. The rock-lever 54 is given intermittent movements through a rotary cam-wheel 62 loosely mounted upon the main-shaft 1 and formed with a slot s to receive a stud 63 carried by the said lever. The cam-wheel 62 is formed with the horizontally extending teeth 62^x between which successively enter the horizontally-extending pins 64, 64', of a lever-dog 65 embracing an eccentric 67 on the main-shaft 1. The dog 65 is formed with a socket in its under peripheral face to receive for pivotal connection by means of pin 64' the vertically extending arm 66^x of a fulcrum-guide 66 which is slidingly fitted within a seat formed in the bed A of the machine and serves to maintain the lower end of the dog stationary when the other end of the same is swung to rotate the cam-wheel 62. It will be understood that when the shaft 1 is rotated the eccentric 67 will move the lever-dog 65 upwardly until the pin 64 enters between two of the teeth 62^x of cam-wheel 62, whereupon the dog will be swung upon its pivotal connection with fulcrum-guide 66 to impart a semi-rotation to the cam-wheel. Continued rotation of the eccentric 67 will move the dog downwardly to disengage its pin 64 from the teeth of the cam-wheel and to engage its holding pin 64' with the wheel so as to hold the latter stationary when in the continued rotation of the eccentric the dog is swung to initial position. As hereinbefore pointed out the mechanism just described is similar to that disclosed in patent to Diehl No. 541,840, of July 2, 1895, and may be substituted by other suitable mechanism for the same purpose.

Having thus set forth the nature of the invention, what I claim herein is:—

50 1. In a sewing machine, the combination with stitch-forming mechanism, of a ruffler-blade, means for imparting endwise reciprocatory movements in a fixed direction to said blade, and means for moving the said blade bodily laterally to lay the ruffles in different positions relative to the line of stitching.

2. In a sewing machine, in combination, stitch-forming mechanism including a reciprocating needle, feeding mechanism, a ruffler-blade having an active fabric-engaging edge-portion, and means for maintaining said edge-portion in fixed angular relation to the line of feed while reciprocating

said blade endwise and moving it laterally to lay the ruffles in different positions relatively to the line of stitching.

3. In a sewing machine, in combination, stitch-forming mechanism including a reciprocating needle, feeding mechanism, a ruffler-blade, a supporting plate between which and said ruffler-blade the material to be ruffled passes, means for imparting reciprocatory ruffling impulses to said blade and plate, and means for moving said blade and plate laterally to lay the ruffles in different positions relatively to the line of stitching.

4. In ruffling mechanism for sewing machines, the combination with a ruffler-blade 80 of a carrier for said ruffler-blade adapted to receive and guide a tape, and means for imparting transversely directed movements to the said carrier.

5. In ruffling mechanism for sewing machines, the combination with a ruffler-blade and a carrier for said blade adapted to receive, and having edge-guiding walls for, a tape, of means for varying the distance between the edge-guiding walls of the carrier, means for reciprocating the said carrier, and means for moving said carrier laterally.

6. In ruffling mechanism for sewing machines, the combination with a supporting bracket, of two ruffler-blade carriers relatively movable upon the said bracket and formed with vertical guide-walls, ruffler-blades adjacent the said guide-walls, and means for adjusting the carriers to vary the spacing between the said guide-walls.

7. In ruffling devices for sewing machines, a ruffling-guide comprising two relatively-adjustable sections, the first section being formed with horizontally-disposed upper and lower guiding walls and an intermediate vertical guide-wall, the second section being slidingly fitted between the upper and lower guiding walls of the first section and formed with a vertical guiding wall parallel with the corresponding wall of the first section, and a ruffler-blade sustained by one of the said sections.

8. In ruffling devices for sewing machines, the combination with a supporting bracket formed with a guideway, of a ruffler-blade, a carrier for said ruffler-blade having a member slidably mounted in the bracket-guideway and formed with horizontally-disposed spaced plates and a vertical guide-wall, a second ruffler-blade and a carrier therefor interposed between the said carrier-plates and having a vertical guide-wall means for relatively adjusting the said carriers, and means for reciprocating the said carriers.

9. In ruffling devices for sewing machines, a tape guide-member formed with upper

and lower horizontally-disposed guide-walls and an intermediate vertical guide-wall, a second guide-member fitted between the upper and lower walls of the first-named guide-member, a supporting bracket for the said guide-members, a lever carried by said bracket and connected with and adapted to

relatively move the said guide-members, and a ruffler-blade carried by one of said guide-members.

In testimony whereof, I have signed my name to this specification.

ALBERT H. DE VOE.
